DESIGN FOR A CHANGEABLE SIGN OR THE LIKE

Anton F. Hren, Chisholm, Minn.

Application August 2, 1937, Serial No. 70,803

Term of patent 7 years

To all whom it may concern:

Be it known that I, Anton F. Hren, a citizen of the United States, residing at Chisholm, in the county of St. Louis and State of Minnesota, have invented a new, original, and ornamental Design for a Changeable Sign or the like, of which the following is a specification, reference being had to the accompanying drawing, forming part thereof.

I claim:

The ornamental design for a changeable sign or the like, as shown.

ANTON F. HREN.
